ELECTRICALLY LIGHTED WALL
SWITCH PLATE

Thomas L. Wheeler, Jr., Columbus, Ohio

Application February 19, 1945, Serial No. 578,691

3 Claims. (Cl. 240—2)

1
This invention relates to an electrically lighted wall switch-plate.

An object of this invention is the production of an automatic safety light and pilot-indicator in the form of a novel plate designed for application over standard wall type toggle or push-button light switches. It incorporates a low-wattage neon bulb or glow lamp which is so connected that it lights automatically when the light controlled by the switch itself is turned off and goes off when the switch is turned on.

Another object of the invention is the construction of a novel device which presents a combination of novel features. The first of the said featured advantages is that the light emitting from the switch-plate is sufficient not only to indicate the position or whereabouts of the switch in an otherwise dark room, but also provides a degree of illumination which enables a person entering the room from a dark area, or arising from sleep within the room, to distinguish objects or obstacles therein, or to determine the confines of the room itself, with sufficient clarity to avoid collision with such obstacles, objects or confines. The second of these features is that there is no aperture, grille or transparent insert of any kind in the plate through which the light from the neon bulb or glow lamp passes in providing the illumination described above. Instead the bulb is protected from direct view, exposure or accessibility by virtue of being encased entirely beneath and enclosed by the outer surface of the plate, which is specially shaped to provide a cavity, accessible only from the back of said plate. The light from the bulb is thus softened or diffused through the semi-transparent material of which the plate is made, the plate being thin enough on the lower part of the reflector portion to permit light from the bulb or glow lamp to be transmitted over the face of said plate, below the reflector portion.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Fig. 1 is a view in front elevation of a wall switch-plate constructed in accordance with the present invention.

Figure 2 is a diagram, showing a rear perspective view of the switch plate and a perspective view of a common type of wall switch, all connected in electric circuit.

2
Figure 3 is a vertical, central sectional view of the switch plate in its applied position upon a wall switch.

Fig. 4 is a horizontal sectional view, taken on line 4—4, Fig. 3, and looking in the direction of the arrows.

Fig. 5 is a horizontal sectional view, taken on line 5—5, Fig. 3, and looking in the direction of the arrows.

Fig. 6 is a rear view in elevation of the switch-plate, with the detachable parts removed.

Fig. 7 is a fragmentary rear view in elevation of the switch-plate, showing part of the detachable elements thereon.

Fig. 8 is a vertical sectional view, taken on line 8—8, Fig. 7, and looking in the direction of the arrows.

Fig. 9 is a perspective view of the supporting element or plate.

Fig. 10 is a perspective view of the retainer element or plate.

Referring to the drawings, in which I have shown the preferred embodiment of my invention, 1 designates a wall in which the standard wall switch 2 is positioned. Attached by screws 3 to wall switch 2 is my improved and novel switch-plate 4.

The switch-plate 4 is preferably provided with two reinforcing ribs 5 on its back. The wall switch-plate 4 is provided with a semi-transparent outwardly and downwardly extending reflecting bulged portion 6 (Fig. 1), in which is formed an upper cavity or recess 7 (Fig. 6) and a lower cavity or recess 8. These two recesses 7 and 8 are divided by a horizontal partition 10, which at its left-hand end terminates short of the left-hand end of the recesses for the purpose of receiving the wire 11 (Fig. 9).

The upper part of the outwardly-bulged non-perforated integral portion 6 is much thicker in cross section than the lower part thereof. In other words, the lower part of the outwardly-bulged portion is thinner than the upper part. Consequently, the lower part of the outwardly-bulged portion is a light transmitting area while the upper part thereof transmits light to a lesser extent.

A supporting plate 12, of any suitable material, has mounted thereon a glow lamp or neon bulb 13 and a resistor element 14. When the term "plate" is used in this specification and claims, I do so in a broad sense, meaning any unit or element of the same novel construction and desired material, as specified in this case. The resistor element 14 fits into the upper recess 7,

and the neon bulb 13 fits into the lower recess 8 when plate 12 is in position on the switch-plate 4. Two upper inner lugs 15 extend downwardly contiguous to recess 7, and two lower inner lugs 15^a extend upwardly, contiguous to the lower recess 8 (Fig. 6). The supporting plate 12 is of sufficient flexibility to be snapped under lugs 15 and 15^a, whereby the plate 12, as well as the parts carried thereby, are held securely in position against accidental displacement.

The inside of the switch-plate 4 is also provided with a horizontal transverse reinforcing rib 16 that is made of two parts, with the screw-receiving aperture 17 between the inner ends of the parts, Fig. 6. On this two-part reinforcing rib 16, there are two upstanding lugs 18; these lugs will also be known as the lower outer lugs. Two upper lugs 18^a are formed on the switch-plate, and these lugs extend downwardly. Vertical reinforcing ribs 19 are above the two-part reinforcing rib 16; these ribs efficiently hold the ends of the retaining plate 20 (Fig. 10) in place when said retaining plate is in position upon the switch-plate. This retaining plate 20 is preferably of substantially a U-shaped structure. The retaining plate 20 is sprung into position behind retaining lugs 18 and 18^a, as shown in Fig. 7. Positioned between plate 12 and plate 20 is a fibre cover sheet 21, Fig. 8; this cover sheet protects the outer face of the supporting plate 12.

It is to be understood that the retainer plate 20 rests near its end upon the reinforcing ribs 19, making a secure support for said retainer plate, as a snug fit is obtained thereby.

Referring to Fig. 2, 22 designates the line to the resistor, from the terminal 23 on wall switch 2, while 24 designates the line to the neon bulb from the terminal 25 on said wall switch 2. When the units are assembled as shown in Fig. 2, the fibre cover sheet 21 is placed in position, and then the retainer plate 20 is placed in position, whereupon the switch-plate 4 can be placed in position (Fig. 3) so that the retaining screws 3 can be positioned to hold the switch-plate in an operative position with respect to the wall switch 2. Of course, it is obvious that the lever or button 26 is positioned in the elongated central aperture 27 of the switch-plate.

From the foregoing, it will be understood that I have provided retaining means for the supporting plate and its parts, as well as securing and supporting means for the retainer plate, whereby the elements are efficiently secured in an assembled operative position.

It is to be also understood that when the light switch 2 is in the "off" position, the secondary circuit, limited by the resistor 14, draws only enough current through the "opened" primary circuit to light the glow lamp or neon bulb in the switch-plate. When the wall switch is turned "on," thereby "closing" the primary circuit, the draw on the primary circuit is sufficient to drain the secondary circuit, thereby causing the neon bulb to automatically turn off. When the wall switch is turned "off," the operation is reversed and the neon bulb again burns.

Referring to Figure 2, 27 designates the wiring leading to the room light (not shown).

When desired, the position of the retaining

plate 20, as shown in Figs. 7, 8, and 10, can be reversed. The reason for reversing the position of said fibre retaining plate 20 in the general assembly, is to provide for the toggle switch bracket, that in some cases dovetails or sets into the face plate. This is only true when the toggle switch is placed in the switch box when it is absolutely level or flush with the finished wall.

What I claim is:

- 10 1. An electrically lighted wall plate, provided with an outwardly bulged portion having a resistor-receiving upper recess and a bulb-receiving lower recess, a set of lugs overhanging said upper recess, a set of lugs overhanging said lower recess, and said wall plate being provided with outer sets of lugs, whereby a retainer plate can be held upon said wall plate behind said outer set of lugs.
- 15 2. An electrically lighted wall plate, provided with an outwardly bulged reflector portion on its front face, said outwardly bulged reflector portion having therein an upper recess and a lower recess, a horizontal reflector partition dividing said recesses, a set of inner depending lugs and a set of upwardly extending lugs overhanging said recesses, said wall plate also provided with a reinforcing rib, said reinforcing rib being provided with a pair of upstanding lugs, and said wall plate provided near its top edge with a set of depending lugs, cooperating with said set of lugs on said reinforcing rib.
- 20 3. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
- 25 4. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
- 30 5. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
- 35 6. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
- 40 7. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
- 45 8. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
- 50 9. An electrically lighted wall plate, provided with an outwardly bulged reflector portion on its front face, said outwardly bulged reflector portion having therein an upper recess and a lower recess, a horizontal reflector partition dividing said recesses, said partition terminating short of one edge of said recesses, a set of depending lugs overhanging a portion of said upper recess, a set of upwardly extending lugs overhanging a portion of said lower recess, parallel vertical reinforcing ribs near the edges of said recesses, a two-part reinforcing horizontal rib connected to the lower ends of said first mentioned parallel ribs, said two-part reinforcing ribs being provided at their contiguous ends with upstanding lugs, and said wall plate provided near its top with a set of depending lugs, cooperating with said lugs of the two-part reinforcing rib.
